ADHESIVE APPLYING MECHANISM

Harold Scott Buckingham, Bala-Cynwyd, Pa., assignor to Silver Seal Dairy Products Company, Philadelphia, Pa., a corporation of Delaware

Application November 4, 1936, Serial No. 109,192

8 Claims. (Cl. 91—43)

This invention relates to new and useful improvements in adhesive applying devices and more particularly to devices for applying adhesive to the inner wall surface of a package or sleeve so that a bottom, top or like section may be secured therein.

To this end, the invention consists in the novel construction and arrangement of parts herein-after set forth and shown in the accompanying drawings, in which.

Fig. 1 is a fragmentary view partially in section showing the details of construction of an adhesive applying device made in accordance with this invention.

Fig. 2 is a view in elevation taken along line 2—2, Fig. 1.

Fig. 3 is a view in perspective illustrating the device and accompanying mechanism for operating the same; and

Fig. 4 is a fragmentary view in section of one form of package or container in conjunction with which the present invention may be employed.

Referring now to the drawings, and particularly Fig. 1 thereof, the device contemplated by the present invention comprises a hollow shaft or tube 1 which is preferably fixedly mounted parallel to the surface of a base or other supporting structure 2 by means of a standard 3. The outer or left hand end of the hollow tube or shaft 1 is connected by means of a pipe or other suitable means 4 and valves 5 and 6 to a container 7 which is adapted to be filled with a suitable adhesive substance such as glue, paste or the like. The valve 6 is intended to function as a primary shut off valve which may be manually operated at will through its handle 8, whereas the valve 5 located between the valve 6 and the hollow tube or shaft 1 is operative in a manner set forth hereinafter to intermittently control flow of the adhesive material from the container 7 inwardly of the hollow shaft or tube 1 when the shut off valve 6 is open during periods of normal operation and use of the device.

Forming an integral part of the hollow tube or shaft 1 at the opposite or right hand end thereof is a solid disk-like portion 9 having a diameter approximately twice that of said hollow tube or shaft portion 1 and a series of outlets or ports 10 are formed in the shaft 1 inwardly adjacent said disk-like portion 9 for the purpose of permitting flow of the adhesive material outwardly from the interior of said hollow shaft or tube 1.

A head 11 constituting the adhesive applying member is slidably mounted upon the hollow tube or shaft 1 for reciprocal movement longitudinally

thereof and comprises a main body member 12 and an end or face plate 13. As shown, a recess or chamber 14 of substantial depth is formed inwardly from the right hand end thereof coaxially with respect to the hollow tube or shaft 1 and the diameter of said recess 14 is substantially equal to that of the solid disk-like end portion 9 of the hollow tube or shaft 1 so that the latter will fit snugly within the recess 14 for relative movement axially thereof after the manner of the movement or operation of a piston within a cylinder.

A plurality of communicating passages 15 are formed circumferentially of the body portion 12 and incline outwardly from adjacent the inner end of the recess 14 to an annular groove or channel 16 in the outer face of the body portion 12 substantially midway between the recess 14 and the periphery of said body portion 12, and a plurality of grooves 17 extend radially outward from the annular groove or channel 16 and provide connecting passages between the latter and discharge ports or outlets 18 which open into the peripheral face of the body member 12.

The end or face plate 13 is secured to the body member 12 by any suitable means such as screws 19 and the surface of said plate 13 which contacts the body member 12 is provided with a series of radially extending grooves or slots 20 therein which are suitably positioned circumferentially 30 of the plate 13 so as to overlie the previously mentioned channel 16 and grooves 17 and cooperate therewith to form a second series of outlet openings or ports 21 in the peripheral face of the head 11.

Reciprocation of the head 11 with respect to the hollow tube or shaft 1 and its solid disk-like end portion 9 is effected or accomplished in the present instance by means of a shaft 22 which is journaled in standards 23 and provided with relatively spaced radial arms 24 having slots 25 in the extremities thereof which are engaged by pins or studs 26 projecting laterally from opposite sides of the body portion 12 adjacent the inner end thereof. The shaft 22 is rocked in alternate 45 directions as indicated by the arrow in Fig. 3 of the drawings by means of a crank arm 27 the radial extremity of which is connected to a rocker arm 28 by means of a link or other similar connecting element 29.

The rocker arm 28 is pivotally mounted adjacent its midpoint at the upper end of standard 30 by means of a shaft, spindle or the like 31 and actuated by means of a cam 32 which is fixed upon a shaft 33 driven from a suitable source of 55

- rotary power (not shown) and peripherally contacted by a cam roller 34 rotatably mounted at the lower extremity of a depending arm or leg 35 at one end of said rocker arm 28. Thus it will be observed that during each revolution of the cam 32 the head 11 will be actuated through one complete reciprocatory cycle from the position shown in solid lines in Fig. 1 to the position shown in dot and dash lines and back again.
- 10 In addition to reciprocating or actuating the head 11 with respect to or upon the hollow tube or shaft 1 and its solid disk-like portion 9, the rocker arm 28 also functions to operate the control valve 5 through a crank 36 having a sliding connection with a bar 37 suitably secured or mounted upon the adjacent face of the rocker arm 28 so that said valve 5 will be open to permit the free flow of adhesive from the container 7 to the hollow tube or shaft 1 during the advance 15 stroke or movement of the head 11 to the right with respect to Fig. 1 of the drawings and into the adjacent end of a package, container or like article 38 to which adhesive is to be applied and close the valve 5 to shut off the flow of adhesive 20 to the hollow tube or shaft 1 during return or reverse movement of the head 11 to the left with respect to Fig. 1 of the drawings as it is withdrawn from the adjacent end of the package or container 38.
- 25 30 The containers, packages or other articles to receive adhesive from the head 11 are designated generally by reference numeral 38 and are successively positioned in coaxially spaced relation with respect to the hollow tube or shaft and said head 11 to receive the latter as actuated into the position shown in dot and dash lines during the advance or working stroke thereof. Assuming a container, package or the like 38 to be positioned in the relation shown in dot and dash lines 35 of Fig. 1 of the drawings with respect to the head 11, the latter is actuated to the right in the manner previously described inwardly of the adjacent end of said container or package 38. The recess 14 and associated communicating passages are 40 substantially filled with adhesive material fed through the hollow tube or shaft 1 through the outlet openings or ports 10 therein and as said head 11 travels to the right with respect to said hollow tube and shaft 1 and its disk-like end portion 9, the latter functions as a piston within the recess 14 to compress the adhesive material within said recess and associated communicating 45 passages and cause the same to be discharged outwardly or radially through the openings or ports 17 and 21 in the peripheral surface thereof and deposited onto the adjacent inner wall surface of the container or package 38.
- 50 As return or withdrawal of the head commences, the valve 5 controlling the flow of adhesive from the container 7 to the hollow tube or shaft 1 is closed thus creating a partial vacuum at the tube side of the valve 5 and enabling the disk-like head 9 to exert a suction force or pull on the adhesive remaining in the recess 14 and its 55 communicating passages tending to withdraw said adhesive from the neighborhood or area of the discharge ports and prevent further discharge or dripping of the adhesive from the head 11 when withdrawn from within the article 38.
- 60 65 70 75 It will be obvious that the adhesive distributing head 11 may be of any desired configuration or shape other than that shown and described herein. So too, while specific details of construction of the present invention have been described and illustrated, it is not intended that said invention

shall be limited thereto, but that changes and modifications in such details of construction and arrangement of parts may be incorporated therein within the scope of the annexed claims.

I claim:

1. An adhesive applying device comprising a reciprocating distributing head having a chamber therein and discharge ports communicating therewith, a relatively fixed feeding tube extending through said head for supplying adhesive to the chamber thereof, and an enlarged piston-like extremity on said tube slidably occupying said chamber, said piston-like extremity being operative in one stroke of each cycle of reciprocation of said head to exert pressure on the adhesive in the chamber and discharge the same outwardly through said discharge ports and in the other stroke to create suction in said chamber tending to withdraw adhesive from the neighborhood or area of said discharge ports.

2. An adhesive applying device comprising a reciprocating distributing head having a chamber therein and discharge ports in the peripheral surface of said head communicating therewith, and a relatively fixed feeding tube for supplying adhesive to the chamber including an enlarged piston-like extremity slidably occupying said chamber and operative in one stroke of each cycle of reciprocation of said head to exert pressure on the adhesive in the chamber and discharge the same outwardly through said discharge ports and in the other stroke to create suction in said chamber tending to withdraw adhesive from the neighborhood or area of said discharge ports.

3. An adhesive applying device comprising a reciprocable distributing head having a chamber therein and discharge ports communicating therewith, a relatively fixed feeding tube for supplying adhesive to said chamber, means for reciprocating said head, and a relatively fixed piston-like element slidably occupying the chamber in the head and operative in one stroke of each cycle of reciprocation of the head to exert pressure on the adhesive in said chamber and discharge the same outwardly through said discharge ports and in the other stroke to create suction in the chamber tending to withdraw adhesive from the neighborhood or area of the discharge ports.

4. An adhesive applying device comprising a reciprocable distributing head having a chamber therein and discharge ports communicating therewith, a relatively fixed feeding tube for supplying adhesive to said chamber, means for reciprocating the head, and piston-like means forming a part of said feeding tube slidably occupying the chamber in said head and operative in one stroke of each cycle of reciprocation of the head to exert pressure on the adhesive in said chamber and discharge the same outwardly through said discharge ports and in the other stroke to create suction in the chamber tending to withdraw adhesive from the neighborhood or area of the discharge ports.

5. An adhesive applying device comprising a reciprocating distributing head having a chamber therein and discharge ports communicating therewith, a relatively fixed feeding tube for supplying adhesive to the chamber including an enlarged piston-like extremity slidably occupying said chamber and operative in one stroke of each cycle of reciprocation of said head to exert pressure on the adhesive in the chamber and discharge the same outwardly through said discharge ports and in the other stroke to create suction in said chamber tending to withdraw adhesive from the neighborhood or area of the discharge ports.

hesive from the neighborhood or area of said discharge ports, a valve controlling the feed of adhesive through said tube, and means operative in timed relation with reciprocation of the head 5 to open said valve during the first mentioned stroke of each cycle of said head and close the valve during the other stroke thereof.

6. An adhesive applying device comprising a reciprocable distributing head having a chamber 10 therein and discharge ports communicating therewith, a relatively fixed feeding tube for supplying adhesive to said chamber, means for reciprocating the head, relatively fixed piston-like means slidably occupying the chamber in said 15 head and operative in one stroke of each cycle of reciprocation of the head to exert pressure on the adhesive in said chamber and discharge the same outwardly through said discharge ports and in the other stroke to create suction in the chamber 20 tending to withdraw adhesive from the neighborhood or area of the discharge ports, a valve controlling the feed of adhesive to said chamber, and means actuated by the first mentioned means for opening said valve during the first mentioned 25 stroke of each cycle of said head and close the valve during said other stroke thereof.

7. An adhesive applying device comprising a distributing head having a chamber therein and discharge ports communicating therewith, means 30 for supplying adhesive to said chamber, piston-like means slidably occupying said chamber, and

means operative to effect relative reciprocation of the head and said piston-like means to cause the latter to exert pressure on the adhesive in the chamber and discharge the same outwardly through said discharge ports in one stroke of each cycle of reciprocation of said head and piston means and in the other stroke thereof to create suction in said chamber to withdraw adhesive from the neighborhood or area of the discharge 10 ports.

8. An adhesive applying device comprising a distributing head having a chamber therein and discharge ports communicating therewith, means for supplying adhesive to said chamber, piston-like means slidably occupying said chamber, 15 means operative to effect relative reciprocation of the head and said piston-like means to cause the latter to exert pressure on the adhesive in the chamber and discharge the same outwardly through said discharge ports in one stroke of each 20 cycle of reciprocation of said head and piston means and in the other stroke thereof to create suction in said chamber to withdraw adhesive from the neighborhood or area of the discharge 25 ports, a valve controlling the feed of adhesive to said chamber, and means controlled by the means for reciprocating the head and piston for opening said valve during the first mentioned stroke and closing the valve during said other stroke.

30

HAROLD SCOTT BUCKINGHAM.
